1883.

Chamney Stoves' Design for Clock Case Front.

Des. 883

4-14-1857

Patented April 14, 1857.

Dec. 883

Chamney Jerome of New Haven, Conn:
Letters Patent No. 883. Dated April 14.th 1857.

The schedule referred to in these letters Patent and making part of the same.

To all whom it may concern:

Be it known that I, Chamney Jerome, of New Haven, in the County of New Haven, and State of Connecticut, have invented or produced a new and original design for a Clock-Case Front; and I do hereby declare that the following is a full, clear and exact description of the same, reference being had to the annexed drawings, making a part of this specification, in which

Fig: 1, is a front view of a clock-case, constructed according to my design.

Fig: 2, is a horizontal section of do. &c. &c, fig: 1, showing the plane of section.

Fig: 3, is also a horizontal section, y, y, fig: 1, indicating the plane of section.

Similar letters of reference indicate corresponding parts in the several figures.

A, represents a sill which forms the base of the clock front; and B, B, represent two jamb-posts, on each of which is placed a pilaster C; a cap-plate D, rests upon the upper ends of the jamb-posts B, B, and a top rail E, is fitted between the upper ends of the jamb-posts directly underneath the cap-plate D, and a bottom rail F, is fitted

between the lower ends of the jamb posts, the bottom rail *F*, resting upon the sill or base *A*. The two rails *E*, *E*, are flush with the jamb posts, the pilasters *C*, projecting, of course, beyond both, see fig: 3.

G, is the door, of rectangular form, and fitted between the two jamb posts *B*, *B*, and top and bottom rails *E*, *E*. The door is set a little back within the jamb posts, so that the latter may project a little in front of it, see fig: 3.

On the cap plate *D*, a panel *H*, is placed and fitted between two small pilasters *I*, *I*. The top of the panel *H*, is beveled or inclined downward, each side of its centre, as shown in fig: 1, and the panel *H*, and pilasters *I*, *I*, form the top ornament of the clock front.

What I claim as new and desire to secure by Letters Patent, is:

The base *A*, pilasters *C*, *C*, on the jamb posts *B*, *B*, cap plate *D*, panel *H*, pilasters *I*, *I*, and door *G*, when the whole are arranged specifically as herein shown and described to form a new and original design for a clock base front.
